UNITED STATES PATENT OFFICE

GEORGE W. SWIFT, JR., OF BORDENTOWN, NEW JERSEY.

FEED MECHANISM.

1,353,088.

Specification of Letters Patent. Patented Sept. 14, 1920.

Original application filed November 7, 1917, Serial No. 200,698. Divided and this application filed February 17, 1919, Serial No. 277,550. Renewed December 19, 1919. Serial No. 346,187.

To all whom it may concern:

Be it known that I, GEORGE W. SWIFT, Jr., a citizen of the United States, residing at Bordentown, in the county of Burlington and State of New Jersey, have invented certain new and useful Improvements in Feed Mechanisms, of which the following is a specification.

The object of this invention is to provide 10 an improved feed-mechanism particularly useful for feeding sheet blanks of cardboard, tin, etc., into machines designed to operate upon said blanks to produce boxes, cartons, or containers therefrom, the same 15 being a division of application Serial No. 200,698, filed November 7, 1917.

The improved feed-mechanism comprises in combination with a table, a plurality of 20 parallel shafts carrying sprocket-wheels and chains extending between corresponding wheels upon said shafts, said corresponding wheels being out of alinement, and guide means against which blanks are moved under the action of said chains.

25 The invention further comprises certain novel details of construction and operation hereinafter brought out in the following description, when read in conjunction with the accompanying drawings, in which Figure 1 is a plan view of a feed-table equipped with the preferred embodiment of the improved feed-mechanism; Fig. 2 is a vertical longitudinal section of the same; and Fig. 30 3 is a diametrical section through the feed-mechanism driving-unit.

Referring to the drawings, the mechanism 40 of the feed-table is operated by a pinion 1, driven from an external source of power (not shown), said pinion being secured by means of an adjustable disk 2 to a shaft 3, carrying spaced sprocket-wheels 4 and supported by the oppositely positioned channel irons 5 in turn supported by legs 6. To the shaft 3 is secured a hand-wheel 7, while 45 the gear 1 may be freed from unitary relation with the disk 2 by loosening suitable set screws or bolts 8, said gear also being provided with diametrically oppositely disposed pins 9, with which is adapted to co-operate a latch-member 10, pivotally mounted at 11, upon a projection from the machine frame.

50 Adjacent to the forwardmost end portion of the feed-table is revolvably mounted a shaft 12, also revolvably supported by the

channel irons 5 and carrying spaced sprocket-wheels 13, out of alinement with the said sprocket-wheels 4 (as shown in Fig. 1), while between them travel parallel sprocket-chains 14 in a diagonal direction, connected by angle feed bars 15, the tension of said sprocket-chains being maintained as desired by means of idlers 16, carried upon the free ends of depending pivotally mounted members 17.

In adjusting the feed-mechanism for a given machine with which it is to be used, said machine is stopped in such a position that the parts of the machine adapted to operate upon a blank fed thereinto are in a given position, at which the latch-member 10 is moved into engagement with one of the pins 9, carried by the gear 1. Said gear is then freed from its shaft 3 by loosening the bolts 8, and the said shaft is revolved by means of the hand-wheel 7, until the next successive angle feed bar 15 abuts against the rearmost edge of a blank 18 resting upon the table and having its forward edge in its desired relationship with respect to the parts of the associated machine referred to above. The set screws or bolts 8 are then tightened to lock the gear 1 to its shaft, after which each successive blank is fed into the machine in the desired relation thereto.

During this feeding operation, it is obvious that the friction between the rear edge of the sheet blank and the angle bar 15, moving in a diagonal path across the table, causes the blank to also progress in a diagonal path, thus maintaining said blank in constant uniform contact with a side guide, which in this case comprises an angle-iron 19, adjustably positioned by means of set-screws 20, said guide determining the position transversely of the associated machine at which the blank enters the same.

The feed-table 21 used with this mechanism is supported by the channel irons 5, and above the rear portion is a platform 22 carrying the stack 23 of blanks to be fed. Said table is also provided with diagonal slots or apertures 24 in which the feed sprocket-chains 14 move. In this construction, it is noticeable that with the shafts 3 and 12 parallel and perpendicular to the lateral irons 5, said shafts are readily driven without the necessity of resorting to bevel gears, or their equivalent, while the sprocket-chains 14 can still progress diagonally by 110.

virtue of their transverse flexibility with every attendant advantage of diagonally running belts, and the like, extending between diagonally positioned pulleys.

5 Having thus described my invention, what I claim and desire to protect by Letters Patent of the United States is:—

1. In a machine of the character set forth, the combination of a feed table, a side guide upon said table, feeding means traversing said table in a path inclined from the longitudinal toward said side guide and having sheet engaging members adapted to frictionally engage the rear edge of a sheet and push it forward in said inclined path until the sheet engages the side guide and then slip laterally upon and complete the advance of the sheet parallel with the guide.
- 20 2. In a machine of the character set forth, the combination of a feed table, a side guide upon said table, feed chains traversing said table in planes inclined from the longitudinal toward said side guide and members upon said chains extending above said board transversely of said guide adapted to frictionally engage the rear edge of a sheet to push the sheet forward and laterally in said inclined path until it engages said guide and then slip upon the edge of the sheet until its forward movement is completed.

3. In a machine of the character set forth, the combination of a feed table, a side guide upon said table, feed chains traversing said table in planes inclined from the longitudinal toward said side guide, and transverse

feed bars connecting said chains and movable therewith in a path inclined toward said guide while maintaining their angular relation to said guide.

4. In a feed-mechanism, a plurality of parallel shafts, sprocket-wheels carried by said shafts, a guide in a plane perpendicular to the longitudinal axis of said shafts, endless sprocket-chains mounted upon and extending between said wheels, corresponding wheels upon said shafts being out of alignment to cause said chains to extend in paths inclined transversely toward said guide, and feed bars carried by said chains adapted to shift objects toward said guide as they progress through the machine.

5. In a mechanism of the character described, the combination of suitable feeding mechanism including members for periodically engaging objects to be fed, a drive shaft for said feeding mechanism, a gear element loosely mounted upon said drive shaft and adapted to be driven by the machine to which said feeding mechanism delivers, means for holding said gear element rigid while the feed mechanism and drive shaft are adjusted with relation to it, and means for adjustably securing said gear element upon the drive shaft.

In testimony whereof I have affixed my signature in the presence of two witnesses.
